ALTAR FOR HOMES

Lawrence J. Murphy, Brooklyn, N. Y.

Application May 24, 1940, Serial No. 336,933

8 Claims. (Cl. 40—130)

This invention relates to new and useful improvements in an altar for homes.

More specifically, the invention proposes the construction of an altar which is adapted to be hung upon the wall and into which a statue is adapted to be placed and which is provided with a novel means for illuminating the same.

A further object of this invention is to characterize the altar by vertical rigid strip for attachment upon the wall which continues at its top into a cross and which is provided at its bottom with a horizontal base arranged in a manner to permit the statue to be placed thereon.

Still further the invention proposes the arrangement of a horizontal top member mounted on said strip at the base of said cross and superimposed above said base in a manner to permit fabric material to be mounted there-between at the sides and back thereof for completing the decorative effect of the altar.

A further object of this invention is the provision of a means for adjustably supporting said top member in a manner to permit the same to be moved away from and towards said base so that the space there-between may be changed as desired to change the height of said altar to accommodate statues of different sizes.

For further compression of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an altar constructed in accordance with this invention.

Fig. 2 is a vertical sectional view on the line 2—2 of Fig. 1.

Fig. 3 is a view similar to a portion of Fig. 1 but illustrating a modification of the invention.

Fig. 4 is a vertical sectional view of Fig. 3.

Fig. 5 is a view of the bracket used for holding the fabric material.

Fig. 6 is a view similar to Fig. 4 but illustrating an adjusted position of the top member.

The altar for homes, according to this invention, includes a vertical rigid member 10 for attachment upon a wall. This rigid member 10 is preferably constructed of wood and continues at its top end into a cross 10a. The cross 10a is provided on its top arm with an eyelet which is adapted to be engaged upon a hook or nail driven into the wall for supporting the altar.

The bottom of the rigid member 10 has a

horizontal base member 12. This base member 12 is preferably constructed of the same material as the rigid member 10 and is fixedly held in position by means of a bracket 13. This bracket 13 has one side engaging the bottom face of the base member 12 and a second side engaging the front face of the rigid strip 10 and is securely attached thereto for assisting in maintaining the base member in a right angular position relative to the rigid member 10.

A horizontal top member 14 is mounted on the strip 10 near the base of the cross 10a. This top member 14 is also constructed of substantially the same material as the rigid member 10 and is arranged in a superimposed position above the base member 12.

Strips of fabric material are mounted upon and depend from the members 12 and 14. More specifically, a strip of material 15 is mounted on the base member 12. This strip of material 15 has a horizontal portion 15a extending across the top face of the base member 12 and a depending portion 15b extending downwards from the peripheral edge of the base member 12. This depending portion 15b is arranged to cover the bracket 13 which holds the base member in position upon the rigid member 10. Likewise, the top member 14 has fabric material 16 depending from its peripheral edge.

Fabric material 17 is mounted between the sides and the back of the base member 12 and the top member 14. This fabric material 17 is a continuous piece and starts at one side of the altar and extends across the back thereof and projects forward along the other side thereof. The intermediate area 17a of the fabric material which engages across the back of the altar is extended across the front face of the rigid member 10 as specifically shown in Fig. 2. Thus any desired religious statue may be placed upon the base member 12 and be viewed through the opening formed between the adjacent sides of the fabric material 17.

A means is provided for illuminating the interior of the altar, and more specifically the statue contained therein. This means comprises an electric lamp 18 mounted upon the top member 14 behind the depending fabric material 17. It further includes a lamp 19 mounted upon the base member 10 adjacent the front edge thereof. An electric wire 20 is provided for connecting the lamps 18 and 19 together and is provided with a plug 21 which is adapted to be engaged into a conventional house outlet for providing the necessary current to illuminate the lamps 18 and

19. The base member 12 is further provided with a means for concealing the lamp 19 from view and for reflecting the light emanating from the lamp into the interior of the altar. This means comprises an upwardly extended rigid member 22 attached to the peripheral edge of the base member 12 to the front of the lamp 19. This rigid member 22 is covered with cloth material 23 as shown in Fig. 2.

The operation of this device is as follows:

The altar is hung upon the wall by engaging the eyelet 11 upon a hook or wall support and a convenient statue is placed upon the base member 12. For illuminating the interior of the altar, and more specifically, the statue the plug 21 is engaged into a conventional house outlet for supplying the required current to illuminate the lamps 18 and 19.

According to the modification of the invention shown in Figs. 3 to 6 inclusive, the construction of the altar is similar to that previously described except for the provision of a means for horizontally adjustably supporting the top member 14' so that the same may be moved from a top position downwards. This means comprises a stud 24 projecting from the back edge of the top member 14' and which engages into a vertically arranged elongated slot 25 formed in the rigid member 10. After passing through the slot 25 a wing nut 26 is threadedly engaged upon the extended portion of the stud 24 for tightly clamping the top member in various fixed positions along the length of the slot 25.

This form of the invention is also provided with a further means for taking up the slack in the top portion of the fabric material 17 when the top member 14' is in its completely lowered position. This means comprises a bracket 27 formed of relatively stiff wire and having substantially the same contour as the top member 14'. This bracket 27 has its ends 27a fixedly attached to the rigid member 10 at the base of the slot 25. The fabric material 17 is securely attached to the bracket 27 by means of stitches 28 for tightly stretching the bottom portion of the fabric material between the peripheral edge of the base member 12 and the bracket 27. Thus when the top member 14' is in its lowered position, as shown in Fig. 4, the top portion of the fabric material 17 which is disposed between the bracket 27 and the edge of the top member 14' will double upon itself and project downwards on the inside of the altar to be concealed from view. As shown in Fig. 6, when this top member 14' is in its upper position, the slack of the fabric will be completely taken up and tautly extended between the bracket 27 and the top member 14'.

In other respects this form of the invention is similar to the previous form and similar parts may be identified by corresponding reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An altar for homes, comprising a vertical rigid strip for attachment on a wall, and at the top continuing into a cross, a horizontal base member mounted on the bottom portion of said

vertical strip, a horizontal top member mounted on said strip near the bottom of said cross and superimposed above said base member, strips of fabric material depending from the edges of said members, and fabric material mounted between the sides and the back of said members.

2. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members, and means for illuminating the interior of said altar.

3. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members and means for illuminating the interior of said altar, said means comprising a lamp mounted upon said top member behind its depending strip of material, a second lamp mounted upon said base member adjacent the front edge thereof, and means for supplying the required current to illuminate said lamps.

4. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members and means for illuminating the interior of said altar, said means comprising a lamp mounted upon said top member behind its depending strip of material, a second lamp mounted upon said base member adjacent the front edge thereof, and a means for supplying the required current to illuminate said lamps, and means on said base member for concealing its lamp and for reflecting light emanating therefrom into said altar.

5. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members, and a bracket for assisting in supporting said base member on said rigid member.

6. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members, means

for horizontally adjustably supporting said top member to move from a top position downwards, and means for taking up the slack of the top portion of said fabric material when said top member is lowered.

7. An altar for homes, comprising a vertical rigid strip for attachment on a wall, and at the top continuing into a cross, a horizontal base member mounted on the bottom portion of said vertical strip, a horizontal top member mounted on said strip near the bottom of said cross and superimposed above said base member, strips of fabric material depending from the edges of said members, and fabric material mounted between the sides and the back of said members, means for horizontally adjustably supporting said top member to move from a top position downwards, and means for taking up the slack of the top portion of said fabric material when said top member is lowered, said first mentioned means comprising a stud extending from said top member and passing through a vertically arranged elongated slot formed in said rigid member, and a wing nut threadedly engaged on said stud for clamping said top member in various adjusted positions along the length of said slot.

8. An altar for homes, comprising a vertical rigid strip for attachment on a wall, and at the top continuing into a cross, a horizontal base

5 member mounted on the bottom portion of said vertical strip, a horizontal top member mounted on said strip near the bottom of said cross and superimposed above said base member, strips of fabric material depending from the edges of said members, and fabric material mounted between the sides and the back of said members, means for horizontally adjustably supporting said top member to move from a top position downwards, and means for taking up the slack of the top portion of said fabrics material when said top member is lowered, said first mentioned means comprising a stud extending from said top member and passing through a vertically arranged elongated slot formed in said rigid member, and a wing nut threadedly engaged on said stud for clamping said top member in various adjusted positions along the length of said slot, said latter-mentioned means comprising a bracket attached to said rigid member at the base of said slot, means for attaching an intermediate portion of said fabric material to said bracket for tautly stretching the bottom portion thereof between said bracket and said base member and for permitting the top portion of said fabric material to be freely extended between said bracket and said top member so that said top member may be moved relative to said base member.
